UNITED STATES PATENT OFFICE.

CHARLES R. STEINER, OF NEW YORK, N. Y.

FREIGHTER.

1,175,483.

Specification of Letters Patent. Patented Mar. 14, 1916.

Application filed April 9, 1915. Serial No. 20,362.

To all whom it may concern:

Be it known that I, CHARLES R. STEINER, a citizen of the United States, residing at Long Island City, New York, in the county 5 of Queens and State of New York, have invented a new and useful Improvement in Freighters, of which the following is a specification.

My invention relates to the elimination 10 of loading- and unloading-operations at the sea- and Great Lake-ports.

The purpose is to achieve greater economy 15 and prompter delivery. The means to achieve this result is the proper combination of inland freight-barges of uniform size and construction and ocean-going ferry-boats, which can carry a number of these barges besides their own load, after they are placed on the same and properly seated and 20 fixed by means of reliable and promptly releasable couplings. For greatest ease in the transfer, the barges are to be floated in and out of the ocean-going vessel (this meaning hereafter also Great Lakes-going 25 vessel). The types of vessels required for this traffic-combination are illustrated in the accompanying drawing, in which:

Figure 1 is the front-view and Fig. 2 the side-view of an inland-going vessel not generally fit for Great Lakes (hereafter called barges). Fig. 3 is the mid cross-section of a sea-going ferry-boat. Fig. 4, in somewhat smaller scale, is the plan-section at water-line of the ferry-boat, loaded with barges. 35 Fig. 5 is a detail, illustrating in vertical section a portion of a vertical coupling. Fig. 6 is another detail, illustrating in horizontal section a portion of a horizontal coupling, connected with the barge.

Similar letters in these views refer to similar parts.

A represents the outer and B the inner bottom of the ship hull, C the outer and D the inner side wall of the same, E a strong, 45 watertight deck, forming a support for barges.

F, G, H indicate a number of upper decks, 50 L, L smokestacks, M, M ventilation-conduits, N a barge, O, O two longitudinal trusses extending usually from upper deck to bottom and from end to end of vessel and built watertight between deck E and next deck above.

P, P indicate floors and braces for service 55 and for lateral wall support.

Q indicates a steering-gear, R a vertical

coupling-device in front, S one of a pair of vertical coupling-devices inside the side walls; T, T are barge seats, fixed on deck of the ocean-vessel, U, U the front walls of 60 the same, usually permanently fixed; V, V are the rear end walls of the ship, constructed as watertight gates.

W, W indicate horizontal couplings.

a indicates a vertical hatch wall or reinforcement of the barge-bottom; b is a casting at the barge-bottom, wherein the coupling-bar d can be moved, so as to fill the hole without projecting.

c represents a portion of the watertight 70 coupling-box, fixed on deck E.

e represents a casting with accurate conical surface, a part of coupling W.

f, f . . . are strong ribs or braces, running from deck E to the next deck above. 75

g and h indicate upper and lower watertight interspaces between these ribs.

The barges N are in general of usual construction, but should have strength to carry full load in the dry space on three prearranged supporting places of the bottom, near couplings R, S, S. They may have arrangements for haulage only or they may carry their own power. They are supplied with vertical coupling-arrangements R, S, S, for holding them down to the cushions T on the ocean-voyage and with two or more horizontal couplings W, which, by means of concave, (conical or wedge-shaped) surfaces on the barge, corresponding to convex surfaces 80 on the ship and the central coupling-bars, provide resistance against longitudinal shifting of the barge. The coupling-arrangements on the barges must be in accordance 85 with those on the mainship as regards distance and sizes, but barges may vary in construction to suit their purposes. 90

The construction of the couplings has no features of novelty except as claimed; a type 100 similar in principle, to that described and claimed by me in U. S. Patent 1,084,975, issued Jan. 20—14 on sectional seagoing vessels is preferred. The space on the main-vessel between the two bottoms is divided in many watertight compartments, connected 105 by pipes with pumps. By filling some of the spaces with water the ship can be trimmed and the draft regulated. When stability-conditions permit the lateral spaces

g and h will, preferably, be used for the 110 same purpose, especially when entering a seaport in order to transfer barges. Draft

regulation by filling and emptying these upper instead of the bottom-compartments will save power for pumping. This is only possible by losing some of the vessel's moment 5 of stability; but this loss is of no consequence in port.

The upper part of the hull, the decks E and the trusses O, O form two approximately prismatic spaces, which are water-10 tight and serve as barge-chambers. Their front-end walls, sometimes formed by the ship hull are usually immovable; however the rear-end walls, also forming a part of the ship hull are constructed as watertight 15 swing-gates, as shown, or may be constructed as watertight sluices with vertical motion. These tunnels, in case of purely freight traffic, may be modified by omission of the outer part of upper deck or decks, 20 in which case the outer walls will reach only as far as freeboard is required and will be supported by cantaliver-action of the ribs f, f, f . . . In such modified ships the trusses O, O must be relied upon for longitudinal strength. The number of longitudinal 25 chambers is not essential to this invention; there may be one, or two, as shown, or more. In all cases these chambers can be set dry and may be used for ordinary cargo, when sufficiently fastened. These arrangements 30 on an ocean ferry-boat, as proposed, will allow to enter the seaport with draft adjusted as needed for transfer of barges and with the latter floating in their chambers up to the waterline, so that, after opening the gates the barges can immediately be hauled off and are ready to begin their inland voyage or lighterage trip. The ferry-boat also, if not otherwise held up, may resume 35 its voyage to another seaport immediately after hauling in other barges, if any, and, while making for the high sea, the couplings may be tightened and the water removed from the barge-chambers. For a long 40 voyage, when stability allows it, all compartments may be freed from water ballast, which may have been necessary for the transfer. During the transfer the floating barges must clear the cushions by a few 45 inches. By lowering the water level the barges can be nearly seated and in tightening the couplings they will be pulled down some, thus slightly increasing the draft. For prompt transfer this is preferred; however 50 the vertical couplings may be omitted by providing cushions T snugly fitting the barge-form laterally and, by changing the ship-draft and emptying the chamber in order to achieve a prompt bearing of the barges on supports.

The ferry boat may be permanently united in a single body or it may consist of detachable sections in accordance with said U. S. Patent 1,084,975. Various easily removable 55 spacers, wedges, etc., for the accurate

and easy location of the barges, to suit coupling-arrangements are not a novel feature although most useful. Haulage-ropes and devices, on shore and on the ferry boat will assist in the transfer, which may be either with fixed ship or with fixed barges. All these necessary devices, besides the arrangements for motive power on the ferry boat constitute none of the features of novelty 70 claimed.

I am aware of several patents for improvements in floating in and out and for carrying over shallow or deep water small vessels in large ones, such, for instance as British Patent No. 2416—1879, by B. T. B. 75 Mills, which seems to be for inland navigation. None of them seems to have found practical application for combined oversea and inland traffic and none of them discloses such means, for promptly and safely seating, coupling and releasing canal barges and lighterage barges on ferry boats, which I firmly believe of the greatest importance 80 for safe and prompt service in deep water.

I am aware, that the elimination of time 85 and cost for breaking bulk has been the subject of another patent (Robt. Gordon, Brit. Pat. 13592, Oct. 14—1884) Gordon's proposition, however differs from mine greatly in method and in vessels. While I propose to haul the barges from ferry boats almost directly on their inland route, to traverse which each barge is suitable, Gordon's procedure requires the disconnection from the ocean vessel of all cargo containers and the 90 connection of the same with an inland going special craft, so as to form a sectional inland-going vessel. Gordon's sea-going vessel is a sectional vessel; the distance between end-sections is variable, while in my case a 95 non-sectional vessel may be used. While Gordon's ocean ship is not seaworthy without the cargo-containers, which can make inland-voyages, in my proposition the ship remains always seaworthy whether loaded 100 with barges or without any of them. Hence, for the purpose of this invention, as set forth, I do not claim as a feature of novelty either sectional inland-going or sectional 105 sea-going vessels. The novelty and usefulness relates neither to war- nor to repair-arrangements as in other inventions, but to 110 combined traffic alone and

Therefore I claim:

1. For combined inland- and oversea-waterborne freight traffic non sectional, shallow-water freight barges of such standard size and construction as to suit prearranged chambers of sea-going ferry boats with sea-gates, said barges provided with 115 special reinforcements, as will be necessary for them to support their full load in the dry space, each barge on three selected supporting surfaces, which are provided on 120 cushions, fixed on the chamber-bottom of 125

130

the ferry boat; each barge provided with sufficiently strong, perfectly uniting, but promptly releasable coupling-devices with contact-surfaces, corresponding in distance and size accurately to reciprocal ones on the ferry boat as described.

2. For combined inland- and oversea-waterborne freight traffic a sea- or Great Lakes-going ferryboat with sea-gates at ends 10 of longitudinal barge-chambers, the latter provided with three seating-surfaces for each barge and coupling-devices, perfectly uniting and promptly releasable and with contact surfaces, corresponding in size and 15 distance accurately to reciprocal ones of the barges as described.

3. On a sea- or Great Lakes-going ferry-boat for combined oversea- and inland-navigation longitudinal barge-chambers with seagates, said chambers extending below 20 and above normal sea-level and having seating cushions to amply clear barge-bottoms and a number of perfectly uniting coupling-devices at prearranged distances, corresponding to those of standard barges; said 25 chambers being either with or without a roof or deck, as set forth.

CHARLES R. STEINER.
